UNITED STATES PATENT OFFICE

157,757

LINE BLIND

Leland S. Hamer, Long Beach, Calif., assignor of
one-fourth to Paul A. Dewhirst, Los Angeles,
Calif.

Application September 2, 1948, Serial No. 148,440

Term of patent 14 years

(Cl. D78—1)

To all whom it may concern:

Be it known that I, Leland S. Hamer, a citizen of the United States, residing in the city of Long Beach, county of Los Angeles, and State of California, have invented a new, original, and ornamental Design for a Line Blind, of which the following is a specification, reference being had to the accompanying drawings, forming a part thereof.

Fig. 1 is a perspective view of a line blind, showing my new design as viewed from the top and one end of the blind; and Fig. 2 is a perspective view as viewed from the bottom and other end thereof.

I claim:

The ornamental design for a line blind, as shown.

LELAND S. HAMER.
